AIR BLOWER LUBRICATION

Reynold Happe, Pittstown, and Edgar P. Turner,
Fanwood, N. J., assignors to The Singer Manufacturing Company, Elizabeth, N. J., a corporation of New Jersey

Application March 15, 1946, Serial No. 654,660

7 Claims. (Cl. 230—207)

1

This invention relates to air blowers, and more particularly to air blowers of the motor driven vane type which are light in weight and are adapted to be transportable by hand.

The present invention has for an object to provide an air blower which may be readily applied, as a unit, upon a standard type electric motor housing.

Another object of the invention is to provide an air blower of extremely simple design such that it will be most inexpensive to manufacture and which will require a minimum of attention during the operation thereof.

A further object of the invention is to provide an air blower with fully automatic lubrication means therefor which are so designed that an operator may determine at a glance whether the unit is being lubricated properly.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

The invention, both in structure and in operation, as well as additional objects thereof, will be best understood from the following description taken in conjunction with the accompanying drawings, in which:

Fig. 1 represents a side elevation, partly in section, of an electric motor and air blower unit embodying the present invention.

Fig. 2 represents a right face view of the unit shown in Fig. 1.

Fig. 3 represents a sectional view taken along line 3—3 of Fig. 1.

Fig. 4 represents a sectional view taken along line 4—4 of Fig. 1.

Fig. 5 represents a sectional view taken along line 5—5 of Fig. 1.

Fig. 6 represents a sectional view taken substantially along line 6—6 of Fig. 2.

Referring more particularly to the drawings, the invention is shown as applied to an electric motor unit comprising a cylindrical sheet metal casing 10 in which is mounted, by means of screws 11, a main motor frame 12. Formed integrally with the motor frame 12 are a plurality of spaced radial cooling fins 13 which engage the inner wall of the casing 10. Provided in two of these fins are threaded holes 14 which are adapted to receive the screws 11.

2

Disposed within the motor frame 12 are the usual stator windings 15 and a rotor shaft 16 which is journaled within ball bearings 17 and 18. These ball bearings 17 and 18 are carried respectively in end bells 19 and 20 each of which is secured upon one end of the motor frame 12 in the usual fashion.

Mounted upon the distal end of the rotor shaft 16 is a fan 21 which is adapted to turn with the shaft 16, thereby to draw air through an aperture 22, provided in an end wall of the casing 10, and to force this air over the motor frame 12 to discharge the same out through the opposite and open end of the casing. Such an air blast is effective to keep the motor at a low temperature.

In order to prevent foreign matter from entering the casing along with the air blast, there is provided behind the opening 22 a wire screen 23.

Secured to the bottom portion of the casing 10 is a base portion 24 provided with four (only two of which are disclosed) rubber feet 25. This base, in the present form of construction, contains a motor capacitor 26.

To facilitate the handling of the present unit, there is provided on the top portion of the casing 10, a handle 27 which is secured thereon by means of screws 28 and nuts 29.

Formed in the outer face of the motor end bell 19 is a cylindrical recess 30 into which is seated a rotor or blower casing 31 which is provided with a plurality of spaced radial cooling fins 32. Formed eccentrically within the casing 31 is a cylindrical rotor chamber 33 lined with a hardened wear sleeve 34. Projecting into this rotor chamber 33, through an aperture 35 in the casing 31, is a reduced end portion 36 of the rotor shaft 16 upon which is mounted an auxiliary rotor or blower element 37. A key 37' locks the auxiliary rotor on the shaft 36. This rotor 37 is provided with radially disposed slots 38 in which are slidably mounted vanes 39 which are adapted to engage the sleeve 34 in response to rotation of the rotor 37.

Disposed over one end of the rotor casing 31 is an open faced lubricant-containing casing 40 provided, as is the rotor casing 31, with radial cooling fins 41. Formed within the casing 40 is a cylindrical opening 42 over which is secured a transparent window 43. Window 43 is secured to the face of the casing 40 by means of four screws 44 which pass through a sealing-ring 45, the casing 40, and casing 31 to be threaded into the face of the end bell 19, thereby to secure the entire pump or blower unit to the motor.

An oiltight gasket 46 is clamped between the

window 43 and the open face of the casing 40 for the purpose of forming with the back wall 47 of the casing a lubricant-containing chamber. The dotted line 48 in Figs. 2 and 3 indicates the usual lubricant level position within the casing 40.

Referring particularly to Figs. 2, 3 and 6, the back face of the casing wall 47 is provided with a pair of arcuately shaped grooves 49 and 50 and a pair of apertures 51 and 52, which apertures, in conjunction with the corresponding grooves, function as intake and exhaust ports respectively. Projecting forwardly from the casing wall 47 is a boss 53 through which the intake aperture or port 51 extends. Referring to Fig. 6, the boss 53 has a reduced end portion 54 extending through the window 43, thereby to permit the rotor 37 to draw air from the outside atmosphere through port 51.

As the direction of rotation of rotor 37 is counterclockwise, as viewed in Figs. 2 and 4, the rotor will draw air through port 51 and into the rotor chamber and then expel the air under positive pressure out of the rotor chamber through the exhaust port 52 and into the lubricant-containing chamber 42. From the chamber 42, the air escapes through a tube 55 mounted within a coupling 56 which is threaded into an aperture 57 provided within the top portion of the casing 40. A flexible hose 58 may be connected to the tube 55 for the purpose of leading the air stream to any desired location.

In order to lubricate properly the rotor vanes 39, there is provided a lubricant-conducting tube 59 which contains a bore or conduit 60 and is threaded into the side of the boss 53. The conduit 60 opens at one end in the port 51 and is provided throughout its length with a wick 62 which extends downwardly into the lubricant. Referring particularly to Figs. 2 and 6, it is to be understood that the action of the air rushing towards the rotor 37, through the port 51, tends to draw the lubricant off the end of the wick 62 and thereafter draws the same over the vanes. The lubricant will, of course, work its way up the wick by capillary action.

The air passing through the rotor chamber will carry a portion of the lubricant out through the exhaust port 52. In order to remove the lubricant from the air before it passes out of the chamber 42, the port 52 is disposed at right angles to the window 43, thereby to direct the lubricant-laden stream directly against the window. By thus forcing the stream to impinge against the window, the lubricant is caused to separate out of the air stream and will drop to the bottom of the chamber 42 and the lubricant-free air will then flow out of the chamber through the tube or discharge nozzle 55.

Provided in the back wall of the rotor casing 31 and concentrically with the shaft aperture 35, is a circular recess or lubricant-collecting chamber 63 which has disposed therein a lubricant-absorbing pad 64 for the purpose of arresting the flow of lubricant along the reduced section 36 of the shaft 16. The lubricant is thereby prevented from entering into the motor housing. Also provided in this back wall of the casing 31 is a groove 65 which connects the recess 63 with an aperture or conduit 66 formed in the casing 31 in line with the intake port 51. The pumping action of the rotor 37 will, therefore, tend to draw air through the aperture 66 to the end that all excess lubricant collected by the pad 64 will be drawn off and will be deposited back in the reservoir formed in the casing 40.

It is to be understood that, essentially, the two opposed casings 31 and 40, when stacked together, form a single enclosed hollow casing with a wall member 47 disposed therein, thereby to form a pair of horizontally opposed rotor and lubrication-containing chambers respectively. As such, the entire unit may be readily applied to an electric motor of the usual type.

It is also to be understood that the lubricant contained within the casing 42 is distributed to the blower or rotor vanes only when the rotor is rotating, and when the rotor is at rest the lubricant has no way in which it can seep into either the rotor casing or into the motor housing. Furthermore, the operator by a mere glance through the transparent window 43, may determine whether the rotor is being supplied with the requisite amount of lubricant. Fresh lubricant may be supplied to the reservoir through the medium of the exhaust nozzle or tube 55.

Having thus set forth the nature of the invention, what we claim herein is:

1. An air blower comprising, a hollow open-faced lubricant-containing casing, said casing being cylindrical in shape and having a substantially flat back wall portion, an air inlet port provided in said wall, an air discharge port provided in the top portion of said casing, a transparent window disposed over the open face of said casing in parallel relation with the back wall portion thereof, a blower mounted on said back wall, said back wall forming part of a housing for said blower, means including a wick to conduct lubricant from said lubricant-containing casing to said blower, and conduit means to direct lubricant-laden air under pressure from said blower through said back wall into said casing so that it will impinge directly against said window thereby to cause said lubricant to drop to the bottom of said casing.

2. An air blower comprising, a hollow open-faced lubricant-containing casing, said casing having a substantially flat and vertically disposed back wall portion, an air discharge port provided in the top portion of said casing, a transparent window disposed over the open face of said casing in parallel relation with the back wall thereof, a blower mounted on said back wall, said back wall forming part of a housing for said blower, an air intake conduit passing through said lubricant-containing casing and connecting said blower with the outside of said casing, means to deliver lubricant from said casing to said intake conduit, and conduit means associated with said back wall for directing the lubricant-laden air directly against said window thereby to cause said lubricant to drop to the bottom of said casing.

3. An air blower unit comprising, a substantially enclosed hollow casing, a common wall member disposed within said casing thereby to form a pair of opposed rotor and lubricant-containing chambers respectively, a rotor disposed within said rotor chamber, said wall member being formed with a pair of apertures therein disposed adjacent the exhaust and suction sides of said rotor respectively, conduit means connecting that suction-side aperture to the outside of said casing, a lubricant-delivering means connecting said lubricant containing chamber with said conduit means, and an air discharge nozzle leading from said lubricant-containing chamber to the outside of said casing.

4. An air blower unit comprising, a substantially hollow open-faced casing, a common wall member disposed within said casing thereby to

form therewith a substantially enclosed rotor chamber, a rotor disposed within said chamber, said wall member being formed with an air outlet port therein adjacent the exhaust side of said rotor, a transparent inspection plate disposed over the open face of said casing in spaced and substantially parallel relation with said wall member thereby to form therewith, and in conjunction with said casing, a lubricant-containing chamber, conduit means connecting the suction side of said rotor with the outside of said casing, means for delivering lubricant from said lubricant-containing chamber to said conduit means, and an air discharge nozzle leading from said lubricant-containing chamber to the outside of said casing.

5. An air blower unit comprising, a substantially hollow open-faced casing, a common wall member disposed within said casing thereby to form therewith a substantially enclosed rotor chamber, a rotor disposed within said chamber, said wall member being formed with a pair of apertures therein disposed adjacent the exhaust and suction sides of said rotor respectively, a transparent inspection plate disposed over the open face of said casing in spaced and substantially parallel relation with said wall member thereby to form therewith, and in conjunction with said casing, a lubricant-containing chamber, conduit means connecting that suction-side aperture to the outside of said casing, a lubricant-delivery means connecting said lubricant-containing chamber with said conduit means, said rotor being operative to deliver lubricant-laden air under pressure through that exhaust-side aperture to impinge against said transparent plate thereby to cause the lubricant to drop to the bottom of said lubricant-containing chamber, and an air discharge nozzle leading from said lubricant-containing chamber to the outside of said casing.

6. An air blower unit comprising, a casing having a transverse wall defining a substantially enclosed rotor chamber, a rotor disposed within said rotor chamber, said casing having an open-faced cavity formed therein adjacent said rotor chamber, a transparent inspection plate horizontally disposed over the open face of said cavity thereby forming therewith a lubricant-containing chamber, conduit means connecting the suction side of

said rotor with the atmosphere, a lubricant-delivery means connecting said lubricant-containing chamber with said conduit means, aperture means in said wall to direct lubricant-laden air under pressure from the exhaust side of said rotor into said lubricant-containing chamber so that it will impinge against said transparent plate thereby to cause the lubricant to drop to the bottom of said lubricant-containing chamber, and an air discharge nozzle leading from the upper portion of said lubricant-containing chamber to the outside of said casing.

7. A rotary compressor comprising, a rotor casing defined by a pair of spaced parallel first and second wall portions, a shaft extending into said casing through said first wall portion, a rotor mounted on said shaft within said casing, said first wall portion having a recess therein surrounding said shaft for the collection of excess lubricant, conduit means connecting said recess with the low pressure area of the interior of the casing, said second wall portion having an outlet port and an inlet port therein, an open-faced lubricant-containing casing disposed over said outlet port, a transparent window disposed over the open face of said lubricant-containing casing and at right angles to said outlet port, means to supply lubricant from said lubricant-containing casing to said rotor, and an exhaust nozzle provided in said lubricant-containing casing at a point remote from said outlet port.

REYNOLD HAPPE.
